UNITED STATES PATENT OFFICE.

IRA ORVILLE WRIGHT, OF BALTIMORE, MARYLAND, ASSIGNOR TO THE FARLOW DRAFT GEAR CO., A CORPORATION OF DELAWARE.

DRAFT AND BUFFING GEAR FOR CARS.

1,004,517.

Specification of Letters Patent. Patented Sept. 26, 1911.

Application filed July 2, 1908. Serial No. 441,647.

To all whom it may concern:

Be it known that I, IRA O. WRIGHT, a citizen of the United States, residing at Baltimore city and State of Maryland, have invented new and useful Improvements in Draft and Buffing Gear for Cars, of which the following is a specification.

The object of my invention is the provision of a draft and buffing gear in connection with a single integral or composite beam, preferably of metal, such as an I, or L, or built up beam, located between the car end sill and body bolster, which gear shall be strong and durable and adapted to withstand the strains and shocks of severe service without derangement or resultant injury to the said beam or car floor frame.

The invention consists broadly in applying to opposite sides of a draft beam, cheek castings having means for supporting followers, providing a space between the followers for a cushioning device, furnishing means for supporting a movable draw bar and also means for connecting the draw bar with the rear follower.

It further consists in certain novelties of construction and combinations of parts as hereinafter set forth and claimed.

The accompanying drawing illustrates an example of the physical embodiment of the invention constructed and arranged according to the best mode I have so far devised for the practical application of the principle.

Figure 1 is a side elevation of the gear, the lower part, with the exception of the friction barrel, being in section on line c—c of Fig. 2. Fig. 2 is a top plan view of Fig. 1 partly in section. Fig. 3 is a cross section on lines A and B of Fig. 1. Fig. 4 shows one of the draft links. Fig. 5 is a side view of an I beam with part of the web removed preparatory to attaching the cheek plates. Fig. 6 is an exterior plan view of one of the cheek plates removed from the I beam.

Referring to the figures, the numeral 1 designates, in this instance, a rolled I beam having top and bottom flanges and a part of the web cut away on the lines a, b, c, d, e, the line from d to e being lower than from c to d to provide ample space for the insertion and removal of the cushioning means;

2, the end sill; 3, a removable casting constituting a head block and carrier for the draw bar; 4, 4, the cheek plates or castings, each plate or casting being formed with a top flange 5, a bottom flange 6, a top vertical web portion 7, an irregular concavo-convex web portion 8 of a trough shape, a flange 9 at the front end for attaching the same by rivets to the end sill, a flange 10 at the rear end for securing the same to the web of the I beam by rivets, an end wall 11, a strengthening rib 12 uniting the wall 11 and the flange 10, vertical strengthening ribs 13 extending from the top and bottom flanges to the central line of the casting, front, middle and rear elongated slots 14, 15 and 16, and suitable strengthening ribs radiating from the slots, as shown; 17, the draw bar having a horizontal slot; 18, the front follower having a slot; 19, the rear follower having a slot; 20, a cushioning device, in this instance consisting of frictional elements in a barrel, and a spring; 21, the slotted draft links; 22, the front key passed through the slots in the cheek plates, links and draw bar; 23, the middle key passed through the slots in the cheek plates, links and the front follower; 24, the rear key passed through the slots in the cheek plates, links and rear follower; 25, the rivets passed through the flanges of the I beam and flanges of the cheek plates; and 26, the rivets passed through the vertical webs of the cheek plates and the web of the I beam.

The several parts and elements are assembled and arranged as shown by the drawing. The front key fits the slot in the draw bar and occupies a central position within the slots of the cheek plates; the middle and rear keys are normally held in the positions shown at the extreme ends of the slots in the cheek plates by the cushioning device; and the middle slot in each link is wider than the key so they can move relative to the same in drawing. It will be noted that the front follower has a slot wider than the key, whereas the rear key fits the slot in the rear follower.

The *modus operandi* is as follows: In drawing the draw bar advances, carrying with it the links and rear follower, the mid-

ble slots in the links moving relative to the stationary middle key. When the cushioning device has been compressed the keys frictionally engaging the metal at the ends of the slots and distribute the strains to the cheek castings at six points or places.

In buffing the rear key is stationary, the draw bar, front follower and middle key move rearwardly and, when the cushioning device is compressed, the supplemental strains are transmitted to the cheek plates at six points or places, and also to the web of the I beam at the rear of the rear follower.

Obviously, the cheek plates or castings in connection with the I beam form a hollow cylinder which possesses great strength with a minimum quantity of metal. The cylinder being closed at the rear end and sides, the links, followers and cushioning device are introduced into the cylinder at the front end, and when they are to be withdrawn the casting constituting the head block and carrier is removed.

While I have shown only one example of the physical embodiment of the invention, I do not intend to limit the scope of the same to such example, as in practice modifications may be introduced without constituting substantial departures.

What I claim is:

1. A draft and buffing gear comprising a single metallic beam, cheek plates secured to opposite sides of the beam and provided with slots for keys, a draw bar, followers, a cushioning device, keys, and links.

2. A draft and buffing gear comprising a single metallic draft beam, trough shaped cheek plates with slots for keys secured to opposite sides of the beam, a draw bar, followers, a cushioning device in connection with the followers, keys within the slots in the cheek plates and engaging the followers, and means for connecting the draw bar with the rear follower.

3. A draft and buffing gear comprising a single metallic draft beam, cheek plates with slots for keys secured to opposite sides of the beam, a draw bar, followers, a cushioning device in connection with the followers, keys within the slots in the cheek plates and engaging the followers, and means connecting the draw bar with the rear follower, said means being located between the cheek plates.

4. A draft and buffing gear comprising a single flanged metallic beam, slotted cheek plates secured to opposite sides of the beam, a draw bar, followers, a cushioning device in connection with the followers, keys in connection with the followers and movable within the slots in the cheek plates, and means connecting the draw bar with the rear follower.

5. A draft and buffing gear comprising an I beam with part of its web removed, slotted cheek plates secured to opposite sides of the beam, a draw bar, followers, a cushioning device in connection with the followers, keys within the slots of the cheek plates, and means connecting the draw bar and rear follower.

6. A draft and buffing gear comprising a flanged metallic beam, slotted cheek plates having flanges riveted to the flanges of the said beam and upon opposite sides thereof, a draw bar, followers, a cushioning device in connection with the followers, keys movable within the slots of the cheek plates, and means connecting the draw bar with the rear follower.

7. The combination with a single metallic beam, of a removable buffer block, trough shaped cheek plates secured to opposite sides of the beam, a draw bar, cushioning means, followers, and means connecting the draw bar with the rear follower; said beam and cheek plates forming a hollow cylinder open at the front end when the buffer block is removed.

8. A draft and buffing gear comprising a single metallic beam, trough shaped cheek plates riveted to opposite sides of the beam and each having a slot, a slotted draw bar, followers, cushioning means, means connecting the draw bar and rear follower, and a key passed through the slot in the draw bar and in connection with the means connecting the draw bar and rear follower and the slots in the cheek plates.

9. The combination in a draft and buffing gear, of slotted supports, a draw bar, front and rear followers, cushioning means in connection with the followers, keys, and means connecting the draw bar with the rear follower; the front follower being movable relative to the key in connection therewith and the said key also being movable within the slots of the supports, and the rear follower and key being stationary in the act of buffing; whereby in buffing the front follower may have an initial movement prior to the rearward movement of the key in connection therewith.

10. A draft and buffing gear comprising a single draft beam, cheek plates secured to opposite sides of the beam, a draw bar, followers, a cushioning device in connection with the followers, three keys, and two links.

11. A cheek plate for a draft and buffing gear having flanges at its edges, a trough-shaped web, and a flange, as 10, at the rear end for attaching the plate to the web of a beam.

12. The combination with a draft beam of two cheek plates, each cheek plate having flanges at its edges, a trough shaped web,

and a slot for the reception of a key, the slots being in line when the plates are united to the beam.

13. A cheek plate for a draft and buffing gear having flanges at its edges, a trough shaped web, and strengthening flanges at the outer surface.

In testimony whereof I affix my signature in presence of two witnesses.

IRA ORVILLE WRIGHT.
